MACHINE FOR PLACEMENT OF CONCRETE
AND THE LIKECorwill Jackson, Ludington, Mich., assignor to
Jackson Vibrators, Inc., Ludington, Mich., a
corporation of Michigan

Application January 6, 1947, Serial No. 720,363

10 Claims. (Cl. 94—48)

1

This invention relates to improvements in machines for the placement of concrete and the like.

The main objects of the invention are:

First, to provide a concrete placement machine which is highly efficient and of large capacity and at the same time adapted for manual manipulation with a minimum of effort on the part of the operator.

Second, to provide a concrete placement machine including a vibratory member adapted to forwardly support a substantial mass of concrete as it is advanced against the same in which the vibratory means act to advance the machine.

Third, to provide a machine of the character described employing a relatively long vibratory member in which the vibrations are of substantially uniform amplitude throughout the length of the vibratory member.

Fourth, to provide a machine having these advantages which is comparatively simple in structure and light in weight and at the same time highly efficient.

Further objects relating to details and economies of the structure will appear from the description to follow. The invention is defined and pointed out in the claims.

A structure which embodies the features of the invention is illustrated in the accompanying drawings, in which:

Fig. 1 is a perspective view of a machine embodying my invention positioned upon forms for the material to be placed, the machine being supported by the forms for advancement over the surface of the material and against the material which may be placed on the foundation of a pavement or other slab to be laid.

Fig. 2 is an enlarged fragmentary view taken on the broken line 2—2 of Fig. 3.

Fig. 3 is an enlarged fragmentary view showing portions of the rear side of the vibratory member and one of the vibration synchronizing or tuning elements mounted thereon.

Fig. 4 is an enlarged fragmentary view in vertical section on line 4—4 of Fig. 1.

Fig. 5 is a fragmentary end view with the handle adjusted to position for tilting the machine on its supporting rollers for translating the machine in inoperative position.

Fig. 6 is a fragmentary top plan view showing portions of the vibratory and screed members and vibration absorbing means therebetween.

It is frequently desirable to provide screeds of the type illustrated of considerable length running up to twenty feet or more in length. In the structure illustrated the plank-like vi-

2

bratory member is vibrated by an electric motor having an unbalanced rotor and this is desirably applied or mounted at a central point. Possibly due to the considerable length and possibly to variations in material, "dead spots" or zones, or nodes may occur, that is, zones in which the amplitude of the vibrations is minimized or objectionably reduced as compared to the vibrations at the point of attachment of the vibrating member.

It is one of the main objects of this invention to provide means whereby these dead spots or nodes may be eliminated or minimized to cause the vibratory member to vibrate with substantially uniform amplitude throughout, and at the same time provide means by which the vibrations impart a highly desirable forward movement to the machine, thereby minimizing the manual effort required to advance the machine.

20 The embodiment of the invention illustrated in the accompanying drawing comprises a vibratory member or element designated generally by the numeral 1 and a trailing screed member designated by the numeral 2. The vibratory member comprises a plank-like member 3 disposed vertically edgewise and which in the embodiment illustrated is of multi-ply stock. This member desirably has a shoe 4 which serves as a wear plate or reinforcing member. Reinforcing and mounting plates 5, 6, 6 and 7, 7 are mounted on the front side of the member 3. The screed member 2 is formed of a plank disposed vertically edgewise and is desirably provided with a shoe 8. The vibratory member and the screed member are connected by vibration absorbing means 9 and 10. These connections are disclosed in my Patent No. 2,449,851 granted September 21, 1948, and are not herein specifically claimed.

40 Rollers 11 are mounted on the rearwardly projecting arms 12 on the screed member 2 and adapted to travel on the forms 13, but being out of engagement therewith when the machine is in operative position supported by the forms 13. Handles 14 are pivotally mounted at 15 on the swiveled members 16 comprising a depending shaft having a pivotal bearing in a sleeve or tubular member disposed at the rear of the screed member 2 as shown in Fig. 5. This permits the vertical and also horizontal swinging movement of the handles which are provided with handle bars 17 at their front ends. With the handles thus arranged the operators may stand at the outer side of the forms 13 and the machine manipulated on the forms.

The hooks 18 are disposed on the vibratory member at its ends and face outwardly so that the handles may be engaged with the hooks as shown in Fig. 5 for tilting the machine rearwardly upon the rollers 11 for manipulation on the screeds or on the ground.

In the embodiment of my invention illustrated the vibrating unit 19 is in the form of an electric motor having a rotor 20 provided with an unbalancing weight 21. The electrical connections are indicated at 22 and 23, the motor being controlled from the switch box 24 on one of the handles. The motor is mounted so that the rotor rotates counter-clockwise as viewed in Fig. 4. This tends to advance the machine on the forms.

As I pointed out, there are frequently "dead spots" or nodes in the vibratory member in which the vibrations are minimized. This appears to be due in part to the comparatively light structure of the vibratory member and partially to the dampening effect resulting from the thrust load on the material treated. However, it should be noted that in long vibratory members of quite heavy structure some parts may vibrate with substantially less amplitude than other parts. I overcome this by providing what I term tuning devices or vibration synchronizing devices or means mounted on the vibratory member. Desirably, the "dead spots" or nodes are determined before the tuning or vibration harmonizing elements are mounted.

My use of the term "dead spots" or "nodes" does not imply complete absence of vibration, but it is used in the sense that in these zones the vibrations are relatively slight in amplitude as compared to other zones, and it is desirable that the vibrations shall be approximately uniform in amplitude throughout the length of the vibratory member, this not only from the standpoint of effective treatment of the material placed, but also in the matter of getting a maximum advance travel as a result of the vibrations.

In the embodiment illustrated the vibration synchronizing assemblies comprise weights 25. These weights are desirably supported in a plane in advance of the front plane of the vibratory member and preferably in substantially the vertical plane of the axis of the unbalanced rotor. The weights 25 are supported by forked or bifurcated supports 26 having angled arms 27, the forwardly projecting ends 28 of which overhang the vibratory member. These arms 27 are tiltably and resiliently supported by means of pins 29 carried by the brackets 30 arranged on the rear side of the vibratory member at or adjacent the top thereof.

The pins 29 are provided with cushioning sleeves 31 of rubber which are received within the collars 32 on the arms 27. Bolts 33 project rearwardly from the vibratory member through the lugs 34, projecting upwardly from the crotch of the support. Spacing sleeves 35 are arranged on these bolts between the lugs and the rear side of the vibratory member. The disk-like cushioning elements 36 of rubber or other suitable resilient material are arranged on the bolts, being supported by oppositely disposed cupped holders 37 and 38, the bolts being provided with adjusting nuts 39 and lock nuts 40. By adjusting these cushioning members 36, that is, increasing or decreasing the resilient supporting action thereof on the weight

supports, the device may be "tuned" to synchronize the vibrations of the vibratory member so that they are of substantially uniform amplitude throughout the length thereof. I am able to accomplish this result, that is, the result of synchronizing the vibrations, without the addition of excess structural weight in the vibratory element itself. The weights 25 are disposed and attached to the vibratory member in zones thereof which vibrate with approximately the greatest amplitude. In the vibratory member illustrated the zones of greatest amplitude are disposed adjacent the upper edge of the vibratory member approximately midway between the rotary unbalancing weight 21 and the end supporting carriages. In operative use of the machine, as the machine advances surplus concrete accumulates forward the lower edge portion of the vibratory member 1. Since the vibrations set up in the vibratory member by the rotary unbalancing weight 21 follow the path of least resistance the amplitude along the upper edge of the vibratory member becomes excessive while the amplitude along the lower edge in contact with the accumulated concrete diminishes to the vanishing point as the load of cement increases forwardly of the lower edge of the vibratory member. The purpose of the weights, particularly on vibratory members of considerable length is to counterbalance the load of accumulated concrete forward the lower edge of the vibratory member. As the excessive amplitude along the upper edge of the vibratory member is restrained by the load of the weights 25 the oscillations are equalized and the vibratory member functions efficiently. In placing concrete of relatively stiff, low water content, it is imperative that vibrations of maximum intensity be transmitted to the concrete and not dissipated in excess amplitude along the upper edge of the vibratory member. The means previously described including the adjusting nuts 39 for adjusting the degree of compression of rubber disk-like elements 36 enables the user to tune the vibratory member to the consistency of the concrete, thus when placing concrete of relatively low water content the nuts 39 are tightened to increase the degree of compression of the rubber elements 36 so that the vibrations in the upper edge portion of the vibratory member are more readily transmitted to the weights 25 which dampens the amplitude of the vibrations in such upper edge portion and increases the amplitude in the lower edge portion contacting the concrete of relatively low water content, conversely concrete of relative high workability or high water content does not restrain the amplitude of vibration of the lower edge portion to the same degree as does the concrete of low water content, hence the nuts 39 are loosened to decrease the force of compression on the cushioning elements 36 so that the vibrations in the upper edge portion are transmitted with less force to the weights 25 which increases the amplitude of vibration in such upper edge portion and decreases the amplitude in the lower edge portion contacting the concrete of relatively high water content.

While in the embodiment illustrated I have shown the reinforcing plates on the vibratory member, satisfactory results may be had without these reinforcing elements. One advantage of the structure is that the parts other than the plank-like vibratory elements may be compactly crated, shipped and readily assem-

bled with a plank or other suitable vibratory member or element by the user. This is a very decided advantage inasmuch as in the completely assembled machines a large amount of material is required for crating, and a relatively large amount of shipping space is also required.

In the embodiment illustrated the guard or retaining members 41 are adjustably mounted on rods 42 to adapt the machine for different widths of pavements. This feature, however, is substantially illustrated in my application for Letters Patent above referred to.

I have illustrated and described my improvements in a highly practical embodiment thereof. I have not attempted to illustrate or describe various adaptations and modifications which I contemplate, as it is believed that this disclosure will enable those skilled in the art to embody or adapt the invention as may be desired.

Having thus described my invention, what I claim as new and desire to secure by Letters Patent, is:

1. In a machine of the class described, the combination of a plank-like shaped vibratory member disposed vertically edgewise and adapted to support at the front thereof a substantial mass of concrete as it is advanced against the same, a plank-like screed member disposed vertically edgewise in substantially rearwardly spaced relation to said vibratory member, vibration absorbing connections between said vibratory and screed members whereby they are connected as a unit and coact to mutually support each other in upright position, an unbalanced rotor mounted on said vibratory member with its axis disposed longitudinally of the vibratory member, rollers mounted on said screed member at the rear thereof, said rollers being normally out of engagement with forms on which the vibratory member and screed members may be supported in operative relation to work, and handles pivotally and swingably mounted at the rear of the screed member adjacent the ends thereof, said vibratory member being provided with hooks forward of the pivotal connection of the handle with the screed with which the handles may be engaged to tilt the assembly rearwardly to be supported by and for manipulation on said rollers.

2. In a machine of the class described, the combination of a plank-like shaped vibratory member disposed vertically edgewise and adapted to support at the front thereof a substantial mass of material treated as it is advanced against the same, an unbalanced rotor mounted on said vibratory member centrally thereof with its axis disposed longitudinally of the vibratory member, a weight support having angled arms projecting forwardly above the vibratory member, pairs of supporting brackets for said arms mounted on the rear side of the vibratory member adjacent the top thereof and provided with arm supporting pins having cushioning sleeves thereon, said arms being provided with collars supported by said cushioning sleeves, a weight mounted on the forward ends of said arms in a plane substantially in advance of the vertical plane of the vibratory member, an adjusting bolt for said arms projecting rearwardly from said vibratory member, said arms being connected at their lower ends and provided with a lug receiving said bolt, there being a spacer sleeve on the bolt between the lug and the said vibratory member, and resilient compressible

cushioning means disposed on said bolt in supporting engagement with said lug, the bolt being provided with means for adjusting said cushioning means.

3. In a machine of the class described, the combination of a plank-like shaped vibratory member disposed vertically edgewise and adapted to support at the front thereof a substantial mass of concrete as it is advanced against the same, an unbalanced rotor mounted on said vibratory member with its axis disposed longitudinally of the vibratory member, a weight provided with supporting arms, brackets pivotally supporting said arms mounted on the rear side of the vibratory member adjacent the top thereof and provided with arm supporting pins having cushioning means thereon, an adjusting bolt for said arms projecting rearwardly from said vibratory member, and resilient compressible cushioning means disposed on said bolt in supporting engagement with said arms, the bolt being provided with means engaging said cushioning means on the side thereof opposite from its engagement with said arms for adjusting said cushioning means.

4. In a machine of the class described, the combination of an elongated vibratory member adapted to support at the front thereof a substantial mass of concrete as it is advanced against the same, an unbalanced rotor mounted on said vibratory member with its axis disposed longitudinally of the vibratory member, means connected to said vibratory member for manually manipulating the same, means for causing said vibratory member to vibrate with substantial uniformity throughout, comprising weight supports having angled arms projecting forwardly above the vibratory member, supporting brackets for said arms mounted on the rear side of the vibratory member and provided with arm supporting pins having cushioning members thereon on which said arms are supported, a weight mounted on the forward ends of said arms, an adjusting bolt for said arms projecting rearwardly from said vibratory member, there being a spacer sleeve on the bolt between the arms and the said vibratory member, and adjustable resilient compressible adjusting means disposed on said bolt in thrust engagement with said arms.

5. In a machine of the class described, the combination of a vibratory member adapted to rest upon forms to be supported thereby for forward advancement thereon, means for vibrating said vibratory member at high frequency comprising an unbalanced rotor mounted on said vibratory member with its axis disposed longitudinally thereof and rotatable in a direction forwardly below its axis to advance the vibratory member, and means for causing said vibratory member to vibrate with substantially uniform amplitude throughout, comprising weight supports having angled arms projecting forwardly above the vibratory member, supporting pins for said arms mounted on the rear side of the vibratory member, there being cushioning means between said pins and said arms supportingly connecting said arms to said pins, the rear ends of the arms projecting down below said pins, a weight mounted on the forward ends of said arms, an adjusting bolt carried by said vibratory member, there being a spacer sleeve on the bolt between the arms and said vibratory member, and resilient compressible cushioning means disposed on said bolt

rearwardly of said arms to receive the thrust of the arms in opposition to said weight, and adjustable means engaging said cushioning means on the side thereof opposite from said arms for varying the resilience of said thrust cushioning means.

6. In a machine of the class described, the combination of a vibratory member adapted to rest upon forms to be supported thereby for forward advancement thereon, means for vibrating said vibratory member at high frequency comprising an unbalanced rotor mounted on said vibratory member with its axis disposed longitudinally thereof and rotatable in a direction forwardly below its axis to advance the vibratory member, and means for causing said vibratory member to vibrate with substantially uniform amplitude throughout, comprising weights provided with supporting arms, supporting pins for said arms extending through said arms to provide pivots therefor, said pins being mounted on the rear side of the vibratory member, there being cushioning means between said pins and said arms, the rear ends of the arms projecting down below said pins and the opposite ends of said arms carrying said weights and extending forwardly of said supporting pins, an adjusting bolt carried by said vibratory member, and resilient compressible cushioning means disposed on said bolt rearwardly of said arms to receive the thrust of the arms in opposition to said weight, and adjustable means engaging said cushioning means on the side thereof opposite from said arms for varying the resilience of said thrust cushioning means.

7. In a machine of the class described, the combination of a vibratory member adapted to rest upon forms to be supported thereby for forward advancement, means for vibrating said vibratory member at high frequency comprising an unbalanced rotor on said vibratory member with its axis disposed longitudinally, a weight, a lever pivotally mounted intermediate its ends to said vibratory member, one arm of said lever supporting said weight adjacent the upper edge of the vibratory member, the other arm of the lever extending downwardly from the pivot thereof, and means for adjustably connecting said downwardly extending arm to said vibratory member.

8. In a machine of the class described, the combination of a plank-like shaped vibratory member disposed vertically edgewise and adapted to support a substantial mass of material treated at the front thereof as it is advanced against the same, means for vibrating said vibratory member carried thereby, means for inducing vibrations of approximately uniform amplitude in spaced relation to said vibrating means comprising a weight and means for resiliently supporting said weight on said vibratory member in substantially spaced relation from said vibrating means and one end of said vibratory member and adjacent the top edge of said vibratory member in a zone of said vibratory member of approximately maximum amplitude

of vibration, and means for varying the resilience of the weight supporting means including means adjustable relative to the vibratory member and disposed relative to said vibratory member and weight supporting means to adjust the limit of the range of movement of the weight supporting means relative to the vibratory member due to the resiliency of the weight supporting means.

9. In a machine of the class described, the combination of a plank-like shaped vibratory member disposed vertically edgewise and adapted to support a substantial mass of material treated at the front thereof as it is advanced against the same, an unbalanced rotor mounted on said vibratory member centrally thereof and with its axis disposed longitudinally of the vibratory member, means for inducing vibrations of approximately uniform amplitude throughout the length of said vibratory member comprising weights and means for resiliently supporting said weights on said vibratory member between said rotor and the opposite ends of said vibratory member and in substantially spaced relation from said rotor and opposite ends and adjacent the top edge of said vibratory member and in zones of said vibratory member of approximately maximum amplitude of vibration of said vibratory member, and means adjustable relative to said vibratory member and disposed relative to said weight supporting means and vibratory member to adjust the limit of the range of movement of the weight supporting means relative to the vibratory member due to the resiliency of the weight supporting means.

10. In a machine of the class described, the combination of a plank-like shaped vibratory member disposed vertically edgewise and adapted to support a substantial mass of concrete at the front thereof as it is advanced against the same, means for vibrating said vibratory member carried thereby, a weight, means for resiliently supporting said weight adjacent the top edge of the vibratory member and in a zone of said vibratory member of approximately maximum amplitude of vibration, and means adjustable relative to said vibratory member and disposed relative to said weight supporting means and vibratory member to adjust the limit of the range of movement of the weight supporting means relative to the vibratory member due to the resiliency of the weight supporting means.

CORWILL JACKSON.
